E. B. Bradford

Attorney

UNITED STATES PATENT OFFICE.

BARNETT WRIGHT MACY, OF JACKSONVILLE, FLORIDA, ASSIGNOR TO ELECTRIC HEATING CORPORATION, OF JACKSONVILLE, FLORIDA, A CORPORATION OF FLORIDA.

ELECTRICALLY-HEATED IRONING DEVICE.

Application filed May 6, 1922. Serial No. 559,016.

To all whom it may concern:

Be it known that I, BARNETT WRIGHT MACY, a citizen of the United States, residing at Jacksonville, in the county of Duval and State of Florida, have invented certain new and useful Improvements in Electrically-Heated Ironing Devices, of which the following is a specification.

My said invention relates to an improved 10 electrically heated ironing device and it is an object of the same to provide a highly efficient device of this character in which the heating element which is immersed in liquid is made of material having a low resistance 15 and is never brought to a very high temperature.

Referring to the accompanying drawing which is made a part hereof and on which similar reference characters indicate similar 20 parts.

The single figure shows a transverse section through a cuff ironer.

In the drawing reference character 10 indicates a cuff ironer of conventional type, the invention, however, not being limited to 25 the particular type of ironing device as the essential features may be utilized in devices of various types for ironing clothing and also for various other purposes. The cuff ironer here shown has a lid 11 securely fastened in place by screws 12, the lid having mounted thereon a valve 13 by means of which the oil or other liquid shown at 14 can be introduced or replenished as needed.

A pair of supports, preferably in the form 40 of rods 15, are secured to the cover in any convenient manner and extend through the same to provide terminals to which conductors may be secured by nuts 15' in conventional manner, the rods being insulated from the cover by bushings 16 and washers 17. At their lower ends the rods are oppositely bent, in this instance, at angles corresponding to the slopes of the lower wall of the cuff ironer and each rod has mounted thereon a 45 cylindrical member 18 of insulating material. These members are held in place by nuts threaded on the rod and are provided with helical peripheral grooves 19 extending from end to end thereof. A closely coiled fine wire 20 of material offering approximately the same resistance to the passage of electricity as does the liquid indicated at 14 or a slightly less resistance is laid about each 50 of the members 18 and along the helical

grooves thereof, being held in place at the ends of the cylindrical members by nuts 21. The intermediate bight of the wire is supported by a rod 22 depending from a hook 23 fixed in a block 24 of insulating material 60 on the cover.

I have shown in the drawings a construction in which the insulators 18 rest on the opposite slopes of the outer casing, the groove for the wire being deep enough to 65 keep it from contact therewith. It will be understood that I may arrange the insulators in other positions in the casing and may vary the structure in other respects within the scope of my invention as defined 70 in the appended claims.

In the operation of the device current will pass through one of the rods 15 to an end of the wire 20 and thence through the wire 20 to the other support 15. In so doing it 75 will heat the wire which by reason of the large number of coils has a very extensive surface and the heat will pass therefrom to the oil or other liquid and will raise the temperature to the desired degree thus forming 80 a reservoir of heated liquid which will transmit the heat equally to all parts thereof and will retain the high temperature for an extended period of time. On account of the low density of the heating element and the 85 even distribution of heat it will be obvious that the wire could not well be heated to incandescent, as in various other electric heaters and similar appliances, and as a matter of fact it is kept at a temperature much 90 lower than that necessary to produce incandescence.

Having thus fully described my said invention, what I claim as new and desire to secure by Letters Patent, is:

1. An electrical ironing device having an internal chamber containing oil and an outer ironing surface, a heating coil immersed in said oil and formed of material having relatively low resistance whereby carbonization of the oil is prevented, said heating coil consisting of a finely coiled wire laid in convolutions to accommodate the wire to the size of the chamber, the liquid being free to circulate through and around the convolutions of the heating coil, substantially as set forth.

2. An electric ironing device having an internal chamber containing a fluid and an outer ironing surface, supporting means

110

within the chamber and a heating element consisting of finely coiled wire of relatively low resistance wound about the supporting means, substantially as set forth.

3. An electric iron having an internal chamber and an outer ironing surface, a pair of supports of conducting material extending through the wall of the chamber and into the interior thereof, insulating

10 means carried by said supports and a heating element of coiled wire carried by the insulating means and connected at opposite ends to the respective supports, substantially as set forth.

15 4. An ironing device comprising a body having a compartment holding a liquid, a heating element consisting of a finely coiled wire disposed in coiled arrangement within the compartment, the liquid surrounding 20 the said coiled wire and filling the space between the convolutions thereof, and means to support the same in spaced relation to the walls thereof, substantially as set forth.

5. An ironing device comprising a body 25 having a chamber holding a liquid and an outer ironing surface, a pair of helically grooved cylindrical insulating devices resting against the wall of the chamber next to the ironing surface, a heating element comprising a finely coiled wire lying in said

grooves and spaced from the ironing surface, means for supporting the insulating devices and means for connecting electrical conductors to the heating element, substantially as set forth.

35 6. An ironing device comprising a body having a V-shaped ironing surface and an internal chamber holding a liquid, a pair of helically grooved insulators resting against walls of the chamber opposite the ironing surfaces, a wire lying in said grooves and spaced from said walls, and means opposite the junction of said walls for supporting the wire intermediate said insulators out of contact with the wall of 40 the chamber, substantially as set forth.

7. An ironing device having a body whose ironing surface is formed by a pair of oppositely sloping walls, and a pair of heating coils within the body, one resting 45 against each of the said walls, substantially as set forth.

In witness whereof, I have hereunto set my hand and seal at Jacksonville, Florida, this 2nd day of May, A. D. nineteen hundred 50 and twenty-two.

BARNETT WRIGHT MACY. [L. S.]
